CLAIM

The ornamental design for a vehicle headlamp, as shown and described.

DESCRIPTION

FIG. 1 is a front view of a vehicle headlamp, according to a first embodiment of the invention.

FIG. 2 is a first perspective view thereof.

FIG. 3 is a second perspective view thereof.

FIG. 4 is a front view of a vehicle headlamp, according to a second embodiment of the invention.

FIG. 5 is a first perspective view thereof.

FIG. 6 is a second perspective view thereof.

FIG. 7 is a front view of a vehicle headlamp, according to a third embodiment of the invention.

FIG. 8 is a first perspective view thereof; and,

FIG. 9 is a second perspective view thereof.

Mirror images of the views are within the scope of the claimed design even if not illustrated.

Features shown in broken lines do not form part of the claimed design.

1 Claim, 9 Drawing Sheets(56)
